ABSORPTION CYCLE REFRIGERATING APPARATUS

Edmund E. Allyne, Cleveland, Ohio, assignor to Allyne Laboratories, Inc., Cleveland, Ohio, a corporation of Ohio

Original application February 7, 1929, Serial No. 338,174, now Patent No. 1,978,662. Divided and this application April 7, 1933, Serial No. 665,029

4 Claims. (Cl. 62—118)

This invention relates to absorption refrigerating apparatus, and this application is a division of my copending application, Serial No. 338,174, filed February 7, 1929, now Patent No. 5 1,978,662 granted Oct. 30, 1934.

The object of this invention is to provide a refrigerator or icebox with absorption refrigerating apparatus and to so arrange and equip such absorption apparatus with suitable means whereby it may be operated by air cooling and without the use of impounded or running water.

In accomplishing this result a suitable cabinet is provided with an apparatus compartment for the condenser, still-absorber, cooling loop and burner. This apparatus compartment is also provided with means forming part of a flue system and communicates with a main upper flue extending preferably up the back of the box and open at the top to the atmosphere whereby the draft created by the flue especially with the heat produced in the cycle will cool the condenser during the heating period and later cool the still to promote absorption during the cooling period.

The invention also contemplates the isolation of a rectifier in an auxiliary flue all its own and controlling the air circulation through such flue to the end of having a rectifier subjected to the ideal temperature for ideal rectifying purposes. Another feature of this invention is the isolation of the evaporator supply and gas return pipe or conduit in a second auxiliary flue to prevent it being subjected to the heat from the still absorber and to promote its ideal functioning in the apparatus.

Still another feature of the invention is a very efficient air cooled loop arrangement for use in cooling the boiler liquor during the cooling period for promoting absorption, circulation in this loop being set up by the returning gas during the cooling period.

Other details of the invention will be brought out in the following description, drawings, and claims.

Referring to the drawings, Fig. 1 is a vertical sectional view taken through the refrigerator from front to rear with parts shown in section and elevation; Fig. 2 is a rear elevation of the box; Fig. 3 is a section on the line 3—3, Fig. 2.

In the embodiment shown in the drawings the refrigerating cabinet comprises a heat insulating casing 1 open at the front to form the refrigerating chamber. The cabinet also includes a lower apparatus compartment 2 open at the front and the walls of which support the refrigerating chamber and its casing. The apparatus compartment 2 is deeper than the refrigerating chamber and is open at the front and at the bottom, the former for access to the apparatus and the latter for providing an open mouth for a flue and for

receiving the condenser, as will appear. Extending from the lower front edge of the apparatus compartment to the back edge of the refrigerating chamber is a flue plate 3 forming with the sides and the back a flue compartment 3' for the condenser, the cooling loop, the burner and the still absorber. The back 4 of this apparatus compartment is continued upward for the full width and height of the box and together with side plates 5 and 6 and intermediate strips 7 and 8, form a main flue 9, a rectifier flue 10, and a gas supply and return flue 11 as shown clearly in Fig. 3. Arranged in the bottom opening of the apparatus chamber 2 and the flue chamber 3' therein is a condenser comprising a plurality of 15 coils 12 arranged in a lower group and an upper smaller group and extending from the front part way toward the back. All of these coils are provided with fins 13 to increase the transfer of the heat to the air current passing up through the 20 flue. Arranged above the condenser and in this flue portion 1 is a still-absorber in the form of a horizontally arranged tank 14. This still-absorber or tank is provided at one of its ends with a pair of downwardly extending conduits 15 25 communicating with the still-absorber at a point above the bottom thereof and with a horizontal loop header 16 connected to a plurality of loop pipes 17 arranged horizontally in a bank or group and all provided with a multiplicity of fins 18 to 30 permit air cooling. These pipes 17 all communicate with another loop header 19 at the opposite end of the still-absorber and this header communicates by a single loop conduit 20 with the bottom of the still. The loop conduit 20 is continued downward in a sump conduit 21 leading to a suitable sump in the form of a long closed end tubular member. Communicating with the pair of loop conduits 15 and extending into their sides are two gas return connections 23 and 24, the former being slightly lower than the latter and both merging into a single gas return pipe 25 entering the side of a trap casing 26 about a third of the way down from its top. This trap casing 26 is closed except for the pipes which enter it. Extending upwardly from the end of the still adjacent the flue 10 is a gas outlet and rectifier tube or pipe 27 which extends to the top of the flue 10 and returns to and enters the trap casing 26 and extends to a point near the bottom thereof and hence below the surface of the liquor therein. The flue 10 is preferably provided with a cross partition or diaphragm plate 28 having an opening 29 therein adapted to be closed by a suitable damper 30 arranged upon the lower end of a 35 thermostatic rod 31 guided in a bracket 32 at the bottom and adjustably mounted in a bracket 33 at the top. The arrangement of this thermostatic rod is such that when the temperature in 40

the flue 10 exceeds the proper rectifying point the damper operates and prevents undue heating so that by arranging the rectifier in its own flue and regulating the temperature in this flue the rectifier may be subject at all times to the best working temperature.

The trap casing 26 is still further provided with a top connection 34 forming a part of a pipe 35 leading down to the top of the condenser as at 10 36. The bottom of the condenser is connected by a pipe 37, extending up through the flue 11 with an evaporator storage tank 38. The bottom of this storage tank is connected to a refrigerating unit or grid comprising the pipes 39 extending 15 back and forth in a horizontal grid and at the far end ending in a sump 40 connected by a pipe 41 with the upper end of a sealing trap comprising the parts 42 and 43, the latter being connected by a cross pressure equalizing pipe 44 20 with the pipe 37. The trap comprising the parts 42 and 43 may be of any preferred construction, it being only necessary that it be of a type for sustaining the proper column of liquid refrigerant in the evaporator as a whole and yet permitting the return of any accumulated boiler liquor to the still through the pipe 44 and the pipe 37. Above the refrigerating grid, formed of the pipes 39, is a heat absorber comprising a pan 45 adapted to rest on this grid and at its rear to snugly fit 25 as at 46 the storage 38. Below the refrigerating grid is a heat insulating slab 47 extending up in the back as at 48 to a point where it contacts with the grid coil. This forms a chamber for ice cube containers 49. The compartment formed 30 above the refrigerating grid is closed by a relatively narrow horizontally extending hinged door 50 while the ice cube compartment is closed by a similar hinged narrow door 51 both of these doors being within the main door 52 of the box. 35

40 The boiler is provided with a main burner 53 having a pilot 54, the latter being arranged to the rear of the still-absorber and directly under the main flue 9 so as to instill a draft upwardly therein. Extending from the flame zone of this 45 pilot down to the main burner is a trailing tube 55 provided with a plurality of closely associated openings 56. This trailing tube is closed at its end near the pilot and is open to the main burner so that when the main burner is supplied with 50 fuel or, in other words, when the fuel is turned on to the main burner a trail of small gas supplies will extend from the pilot to the main burner. These gas supplies will ignite and the flame will trail from the pilot down to the main burner 55 and light it. By this arrangement the pilot may be kept burning all the time to promote circulation of air for cooling the condenser and other parts during cooling period and will not be effective upon the still or other parts. At the same 60 time it will be ready to ignite the main burner at the proper time.

From the foregoing it will be seen that during the heating period heat will be applied to the liquor in the still which will give up its ammonia 65 gas. This gas will rise through the rectifier and be rectified and will pass down below the surface of the liquor in the main trap casing 26, bubble up through this liquid and passing out by the 70 condenser pipe 35 to the top of the condenser where it will be condensed by the cooling action of the air and the pressure created within the device. As the rectified gas collects in the condenser it is forced up through the pipe 37 past 75 the trap 43 and up to the top of the storage 38.

It will flow into the storage and into the refrigerating unit or grid if it be empty and cool to the proper level as determined by trap 43. Any heat carried by this liquid refrigerant will be readily absorbed by the heat absorber which may be in the form of a cake of ice in the container 45, transfer of heat from the storage to this absorber being greatly facilitated by the nesting relation of this absorber about one side of the storage. When the heating period terminates the condenser and still cool by the circulation of air, assisted by the heat, through the flue formed in the apparatus and the liquid refrigerant in the evaporator gasifies and returns by the pipe 37 to the condenser thence through the pipe 35 to the top of the trap and through the loop pipe 25 to the conduits 15 where it bubbles up through the liquor in these conduits and starts the circulation of the boiler liquid therein. The draft in the flue therefore cools the loop and absorption takes place with a consequent refrigeration in the apparatus.

The provision of the flue and the arrangement of the still loop and condenser within the flue is of great importance because the heat generated by the apparatus tends to produce the proper cooling of the parts at the proper time and permits air cooling of the apparatus and does away with the usual impounded and circulating water arrangement.

What I claim is:

1. In a refrigerating apparatus an evaporator, a still-absorber and a condenser connected in operative cycle, and a cooling loop for said still-absorber, said loop comprising a pair of conduits 35 connected to the still-absorber in spaced relation, a header connected to each of said conduits, a plurality of pipes connecting said headers to form a grid and means for leading the gas returning from said evaporator to one of said conduits.

2. In a refrigerating apparatus, an evaporator, a still-absorber and condenser connected in operative cycle and a cooling loop for said still-absorber, said loop comprising a pair of adjacent depending conduits connected at one end of the 45 still-absorber and a single conduit depending from the opposite end of said still-absorber, horizontal headers connected to the pair of adjacent conduits and to the said single conduit, a plurality of spaced apart pipes connecting said horizontal 50 headers to form a grid and a conduit connecting said evaporator and one of said depending conduits.

3. In an absorption type refrigerating apparatus, a still-absorber, evaporator and condenser connected in operative series, a heat exchanger in communication with said still absorber comprising a pair of spaced vertical conduits connected adjacent one end of the still-absorber, a vertical conduit connected adjacent the other end 60 thereof, horizontal pipes connecting the spaced conduits and a heating device for said still-absorber positioned between the said horizontal pipes and the still-absorber and said vertically spaced conduits.

4. In refrigerating apparatus of the character described, a still-absorber, a cooling loop in closed circuit therewith, said loop extending below said still-absorber and in communication therewith adjacent one end thereof by spaced conduits, and 70 adjacent the opposite end of the still-absorber by a single conduit, a heater positioned between the spaced conduits and lying intermediate the still-absorber and the cooling loop.

EDMUND E. ALLYNE. 75
